Primary Examiner — Daniel Bui(74) *Attorney, Agent, or Firm* — GE Global Patent Operation; John A. Kramer(57) **CLAIM**

The ornamental designs for a busbar cleat, as shown and described.

DESCRIPTION

FIG. 1 is a perspective view of a busbar cleat depicting our new design;

FIG. 2 is a first side view thereof;

FIG. 3 is a second view thereof;

FIG. 4 is an end view thereof;

FIG. 5 is an opposite end view thereof;

FIG. 6 is a top plan view thereof; and,

FIG. 7 is a bottom plan view thereof.

The broken line portion of the drawings is included to show unclaimed subject matter only and forms no part of the claimed design.
